UNITED STATES PATENT OFFICE.

JOHN L. COX, OF MURPHYSBORO, ILLINOIS.

COAL SEPARATOR AND GRADER.

1,002,967.

Specification of Letters Patent. Patented Sept. 12, 1911.

Application filed February 11, 1910. Serial No. 543,359.

To all whom it may concern:

Be it known that I, JOHN L. COX, a citizen of the United States, and resident of Murphysboro, Illinois, have invented certain new and useful Improvements in Coal Separators and Graders, of which the following is a specification containing a full, clear, and exact description, reference being had to the accompanying drawings, forming a part hereof.

My invention relates to coal separators and graders, the object of my invention being to construct a machine for separating coarse materials from fine materials, such as lump coal from the finer grades, and at the same time grading the coal to the several different grades as required by the markets and conveying the various grades to the different bins or chutes as desired.

The machine consists of a series of grooved rollers all of which are driven in the same direction so that when coal is delivered to the separator the rollers will separate and grade the coal and at the same time act as a conveyor to direct the coal to the bins or chutes. The grading of the coal is brought about by the different sizes of the rollers and the grooves in the rollers, which rollers are mounted in sets according to the size of the rollers and the grooves therein and the separating and grading is accomplished while the coal is being conveyed from the mine to the bins or chutes without any extra handling.

For the above purposes my invention consists in certain novel features of construction and arrangement of parts as will be herein-after more fully described, pointed out in the claims and illustrated by the accompanying drawings, in which:

Figure 1 is an elevation of the complete apparatus, illustrating the arrangement of the apparatus relative a chute from a mine and the bins or cars to receive the various grades of coal from the apparatus; Fig. 2 is a plan of the complete apparatus; Fig. 3 is an end elevation of the separator and grader with a portion of the separating frame in section; Fig. 4 is an end elevation opposite to the end shown in Fig. 3, and shows the arrangement of the means for imparting motion to the rollers; Fig. 5 is a sectional elevation of a portion of the upper end of the grader illustrating the means whereby the coal, as it is received by the grader, is turned so that slack or the like is

removed from all of the surfaces of the lumps of coal; Fig. 6 is an enlarged, sectional elevation showing the detail construction of one of the rollers and the shaft upon which the roller is mounted, one of the bearings for said shaft and the sprocket wheel secured to the shaft for driving the roller; and Fig. 7 is a detail plan illustrating the means for adjusting the rollers relative each other.

Referring by numerals to the accompanying drawings: 1 designates a chute which leads from the mine or the mine tipple. The chute is provided with an inclined bottom and there is an opening formed in the forward wall of the chute.

Located immediately beneath the chute 1 is a tower 2 and secured to the top of the tower is a pair of bearings 3, and rotatably mounted in the bearings 3 is a shaft 4.

5 designates a pair of parallel I-beams, which beams are connected by the stay-rods 6, there being openings formed through the webs of the I-beams through which the shaft 4 passes, the beams being pivotally carried by the shaft 4. At the ends of the beams, opposite their pivotal ends, are the blocks 7 the bottom faces of which form a seat for the jack screws 8. Embracing each of the screws 8 is a threaded collar 9 having operating handles 10. Arranged to support the jack screws is a frame comprising standards 11 and a cross arm 12, the cross arm being provided with apertures through which the jack screws travel, the collar 9 being supported by the cross arm.

Supported upon the upper faces of the I-beams 5, adjacent their upper ends, is a plurality of journal bearings 13. Mounted for rotation in opposite pairs of the journal bearings 13 are the shafts 14, each shaft being circular in cross section at its ends as shown in Fig. 6 for rotation in the journal bearings 13. The major portion of each shaft is angular in cross section and between the angular portion and the journals is a threaded portion. Embracing each of the angular portions of the shafts 14 is a roller 15 preferably arranged eccentrically relative to the shaft. Each of the rollers 15 is grooved throughout its length, the grooves being arranged at right angles or at an approximate right angle to the axis of the roller. As shown in Fig. 6 of the drawing each of the rollers 15 is preferably made up of separable sections and as shown the lines of separation

of said sections are located in each alternate groove.

Arranged adjacent each end of each shaft 14 is a section 16 the face of which is shaped to conform with the grooved roller and, the locking nuts 17 embrace the threaded portions of the shafts and impinge the sections 16 and clamp all of the sections of the roller together.

10 Alternately arranged relative the ends of the shafts 14 are the sprocket wheels 18 and 19, the sprocket wheels 18 being located on each alternate shaft at the right hand side of the separator and the sprocket wheels 19 being located on each alternate shaft at the left hand side of the separator.

Mounted upon the upper face of the beams 5 is a plurality of journal bearings 20, the base portions of which journal bearings are 20 slotted and the bearings are secured to the beam by means of the bolts.

Mounted for rotation in each pair of journal bearings 20 is a shaft 21, and embracing each shaft is a roller 22 identical in construction with the rollers 15 except that the rollers 22 are concentrically arranged relative their supporting shafts. The rollers 22 vary in size and the depths of grooves vary in the different series of rollers. As 30 shown in Fig. 2 of the drawing, 23 designates a series of the rollers 22, the size of the rollers and depths of grooves therein conveying "lump" and grades of coal other than slack over the rollers.

35 24 designates a series of the rollers, the sizes of which and the depths of grooves therein convey over the rollers all of the coal except the grade known as "pea."

25 designates a series of the rollers for 40 conveying coal thereover all of the grades except the grade known as "nut."

26 designates a series of the rollers for 45 conveying coal thereover the grade known as "lump" and permitting the grade known as "egg" to fall between the rollers of the series. Each of the rollers is provided with a sprocket wheel 27 and 28, the sprocket wheels 27 being positioned upon each alternate shaft at the right hand side of the 50 separator and the sprocket wheels 28 being positioned on each alternate shaft at the left hand side of the separator.

As previously stated, the shaft 4 is a driven shaft, motion being imparted thereto 55 through the medium of the sprocket wheel 29 and chain 30 which leads to any suitable motor. At each end of the shaft 4 is a sprocket wheel 31. Embracing the sprocket wheel 31, at the right hand side of the 60 machine, and embracing the sprocket wheels 18 which impart motion to a number of the rollers 15 and the sprocket wheels 27 which impart motion to a number of the separating and grading rollers, is a chain 32.

65 At the left hand side of the machine and

embracing the sprockets upon all of the rollers not driven by the chain at the right hand side of the machine is a chain 33 which is driven from the sprocket 31 at the left hand side of the driving shaft 4.

Arranged beneath the rollers is a number 75 of hoppers 34 and arranged between each pair of hoppers and at the ends of the end hoppers are the division boards 35 which lead upwardly from the hoppers to a point adjacent the rollers. The hoppers are arranged to conduct the different grades of coal to the cars or bins 36 while the lump coal or largest grade of coal falls over the end of the grader into a separate car or 80 bin 37.

Arranged to parallel the beams 5 is a pair of inclined side boards 38 which serve to retain the coal upon the rollers and arranged to retain the coal upon the rollers 15 is a 85 pair of side boards 39.

In the practical operation of the separator and grader the coal is delivered from the tipple through the chute 1 to the first set of 90 grooved rollers and by reason of the elevation of the first set of rollers the coal, in passing to the next set of rollers, is given a rotary movement. The coal, in passing from the chute on to the rollers and by reason of the agitation caused by the eccentric arrangement of the first set of rollers 95 all of the slack is freed from the lower faces of the coal and is deposited in the car or bin 36 through the first hopper 34. The

coal in passing from the first set of rollers 100 to the second set of rollers is turned, thus all of the faces of the coal are turned so that the slack or dirt thereon is freed from the lumps. The first set of rollers 23, to which the coal is delivered from the receiving 105 rollers 15, is arranged, by reason of their size and the depth of the grooves therein, to separate all of the slack from the coal passing thereover. From the set 23 of the rollers the coal is delivered to the set of rollers 24 110 which are of such size and the depths of grooves therein are of such size as to separate the grade known as "pea." The next set of rollers 25 separate the grade of coal known as "nut" and the rollers 26 separate 115 the grade known as "egg" while the "lump" coal is discharged over the end of the rollers 26. Thus, it is obvious the coal is separated and graded upon a chute the surfaces of which revolve in the same direction as the 120 travel of the coal thereover, and by such a construction the coal is successfully graded without a material breaking up of the lumps.

While I have shown and described the 125 first set of rollers 15 or the receiving rollers as being eccentrically arranged relative their axes and the remaining separating or grading rollers as concentrically arranged relative their axes, I do not wish to be un- 130

derstood as limiting myself to this arrangement of mountings for my rollers. I have found it practical to mount all of the rollers either eccentric or concentric but the construction shown is my preferred construction, that is the arrangement of the receiving rollers being eccentric relative their axes. By this arrangement, that is the eccentric arrangement of the receiving rollers, a greater agitation of the coal is produced at the starting point where all of the coal and all of its grades are delivered to the separator. In this condition it is necessary to free all of the lumps of coal from the first grade or slack. This is readily accomplished, by means of the increased agitation of the receiving rollers due to their eccentric mountings. By reason of the pivotal support of one end of the frame for supporting the rollers, and due to the adjusting means at the opposite end of the roller-supporting frame, I am enabled to vary the incline of the rollers as required to govern the speed of travel of the coal over the separator.

If it is found that the grading is accomplished successfully with the separator held at the greatest incline possible, by means of the jack screws 8, I can increase the capacity of the separator by increasing the speed of the motor.

Such an apparatus I contemplate to use instead of the ordinary revolving screen and find that by its use there is a material difference in operation because of the breakage due to the action of a revolving screen upon the lumps of coal.

I have found that my separator and grader can be successfully used as a "jig" by immersing the entire apparatus in water thereby washing and grading the coal by one operation.

I claim:

1. In a machine of the class described, a frame, means for pivotally supporting one end of the frame, means at the opposite end of the frame for varying the incline of the frame, bearings carried by said frame, means for adjusting the bearings longitudinally of the frame, grooved rollers supported in said bearings, the grooves in different rollers being of different depths, said rollers being arranged in sets according to the depths of said grooves, a separate and distinct set of grooved rollers supported by the frame in a plane above the first mentioned rollers and means for driving all of said rollers in the same direction.

2. In a coal separator and grader, the combination with a frame, means for varying the inclination of the frame, grooved rollers, the grooves in different rollers being of different depths and the rollers arranged in sets according to the depths of said grooves, of a number of grooved rollers supported in a plane above the first mentioned rollers to turn the coal over upon said lower set of rollers.

3. In a coal separator and grader, the combination with a plurality of grooved rollers, the grooves in different rollers being of different depths and the rollers arranged in sets according to the depths of said grooves, of a number of grooved rollers supported in a plane above the first mentioned rollers to turn the coal over upon said first mentioned rollers, and means for simultaneously rotating all of the rollers in the same direction.

In testimony whereof, I have signed my name to this specification, in presence of two subscribing witnesses.

JOHN L. COX.
